UNITED STATES PATENT OFFICE.

AUGUSTUS LAVOIE AND CYRILLE DEMERS, OF LEOMINSTER, MASSACHUSETTS.

NEEDLE-GUARD FOR SEWING-MACHINES.

1,070,823.

Specification of Letters Patent. Patented Aug. 19, 1913.

Application filed December 12, 1912. Serial No. 736,396.

To all whom it may concern:

Be it known that we, AUGUSTUS LAVOIE, a citizen of the United States, and CYRILLE DEMERS, a subject of the King of Great Britain, both residing at Leominster, in the county of Worcester and State of Massachusetts, have invented certain new and useful Improvements in Needle-Guards for Sewing-Machines, of which the following is 10 a specification.

Our invention relates to needle guards for sewing machines and particularly to a guard which will prevent the operators of power driven sewing machines in factories and the like from pricking their fingers.

The object of the invention is to provide a device of this nature, which will protect the point of a needle and at the same time allow an unobstructed view of the needle at all 20 times.

A further object is to provide a device of this character which will allow the needle to be readily threaded without removing the device or altering its position in anyway.

An important object is to provide a device of this character, which may be attached to the presser foot of a machine by means of the screw always found upon the presser foot, and which requires no further means 25 for holding it in position.

Another object is to provide a guard which may be easily vertically adjusted to suit the length of the stroke of the needle bar.

A still further object is to provide a device of this character which is inexpensive in its manufacture, durable, efficient in service, and easily applied.

Other objects and advantages will be 40 made apparent in the course of the following specification.

Referring to the drawings in which like numerals are employed to designate corresponding parts throughout the several 45 views: Figure 1 is a perspective view of our device applied to the presser foot of a sewing machine, Fig. 2 is a side elevation of the guard detached, Fig. 3 is a sectional view on the line 3—3 of Fig. 1, and, Fig. 4 is an 50 end view of the guard detached.

Referring more particularly to the drawings, the numeral 1 designates the head of a sewing machine, in which is mounted the presser bar 2 and the needle bar 3. Secured 55 upon the lower end of the bar 2, by means of the screw 4 is a presser foot 5 of the usual

construction. A needle 6 is held in the needle bar 3 by means of the screw 7 as is customary.

Our device as a whole is designated by 60 the numeral 8 and comprises a horizontal plate 9 having a recess 10 in one of its side edges within which the needle 6 is adapted to reciprocate. Formed integrally with the horizontal plate 9 is an upstanding ear 11 65 provided with a slot 12. Formed upon the lower surface of the horizontal plate 9 or connected therewith, as by means of solder or the like, is an open frame-work 13, which comprises a pair of U-shaped members 14. 70

In use our device is attached to the presser bar by loosening the screw 4, placing the guard in position over the presser foot with the slot 12 registering with the screw 4, moving the device up or down as far as is 75 desired, then tightening the screw 4. It will be noted that by means of the slot 12, the guard may be adjusted vertically with the utmost ease to regulate the device for a long or short stroke of the needle 6, so 80 that the needle will not rise above the top edge of the horizontal plate 9 of the guard. It will be observed that the frame-work 13 allows a perfect view of the needle at all 85 times, offers no obstruction to threading it, and yet will not allow the fingers of the operator to be inserted within the path of travel of the needle.

It will be observed that the recess 10 in the horizontal plate 9 of the guard extends 90 entirely to one edge, thus facilitating the changing of needles. As the point of the needle does not rise beyond the top of the guard, it would be difficult and awkward to change needles unless this cut-out portion 95 extended to the edge, thus preventing the needle from catching against the side of the opening during removal.

Having thus described our invention what we claim is:

1. In combination with a sewing machine, a needle guard detachably and adjustably connected with the presser foot, said guard comprising a horizontal plate provided with a recess in one of its side edges for the 105 passage of the needle, and an open frame-work connected with said horizontal plate and extending downwardly beyond the needle, said guard permitting visibility of the needle at all points in its travel, 110

2. In combination with a sewing machine, a needle guard vertically adjustably and de-

22
tachably connected with the presser foot, said guard comprising a horizontal plate provided with an opening for the passage of the needle, an ear provided with a slot 5 for engagement with a screw upon the presser foot, and an open framework secured upon the lower side of said horizontal plate, said framework comprising a pair of U-shaped members spaced laterally from the 10 needle and extending longitudinally, said framework permitting absolute visibility of the needle, said needle being adapted to have its point disposed below and its eye above said horizontal plate when in its highest 15 position.

3. In combination with a sewing machine, a needle guard adjustably and detachably connected with the presser foot, said guard comprising a horizontal plate provided with 20 a recess in one of its side edges, an attaching ear, and an open frame secured upon the lower side of said horizontal plate, said guard permitting absolute visibility of the

needle at all points, said needle having its eye disposed above and its point below said horizontal portion when in its highest position, for facilitating threading, and said recess facilitating the changing of needles without detaching the guard. 25

4. A needle guard consisting of a horizontal plate upturned at one end for attaching it to the presser foot rod of a sewing machine, and recessed on one side adjacent the other end to permit of the needle point passing below said plate, and downwardly extending loops secured to the under-side of said plate to prevent the operator's fingers coming in contact with the point of the needle. 30

In testimony whereof we hereto affix our 40 signatures in the presence of two witnesses.

AUGUSTUS LAVOIE.

CYRILLE DEMERS.
